WRIST WATCH BAND

George B. Hovey, Cincinnati, Ohio

Application March 16, 1942, Serial No. 434,984

2 Claims. (Cl. 224—4)

This invention aims to provide a novel means for holding a wrist watch or other portable object on the wrist, novel means being provided whereby the device may be adapted to watches of different sizes and to wrists of different sizes.

A mechanic who abides by what is claimed may make changes in the precise structure shown, without departing from the spirit of the invention.

In the drawing:

Fig. 1 shows in top plan, a device constructed in accordance with the invention;

Fig. 2 is an elevation;

Fig. 3 is a longitudinal section taken through the connector vertically;

Fig. 4 is a transverse vertical section taken through the connector;

Fig. 5 is a horizontal section taken through the connector;

Fig. 6 is a plan showing a portion of one of 20 the yokes.

The numeral 1 marks a portable object of any desired sort, for example a wrist watch. As disclosed, but not of necessity, the wrist watch 1 is provided at its ends with pairs of ears 2, carrying connections 3 and 4, in the form of pins.

The numeral 5 marks a curved, U-shaped yoke, including side arms 6, connected by an end member 7. The ends of the side arms 6 carry transverse sockets 8 defining openings which receive the connector 4, the sockets being in end abutment with the ears 2. Adjacent to the sockets 8, the side arms 6 are joined together by a cross piece 9.

The numeral 10 marks an H-shaped yoke which, like the yoke 5, preferably is made of resilient material, such as metal. The yoke 10 is curved after the manner of the yoke 5. The yoke 10 includes side arms 11 carrying transverse sockets 12 receiving the connection 3, the openings in the sockets being designated by the reference character 14. Adjacent to the sockets 12, the side arms 11 are connected by a cross piece 15. At the ends remote from the sockets 12, the side arms 11 have outwardly extended fingers 16.

The numeral 17 marks a connector, which may be of any desired form. Preferably, however, the connector 17 comprises a box-like body 18, which is open at the top, the word "top" having reference to the position which the connector occupies in Figs. 2 and 3. In its side walls, the body 18 is supplied with longitudinally spaced openings or seats 19. Adjacent to one end, the bottom of the body 18 is supplied with an upstanding, concaved anchor 20. There are notches 21 in

the ends of the body 18. The notches 21 at one end of the body receive side arms 6 of the yoke 5, the end member 7 of the yoke being engaged with the anchor 20. The notches 21 at the opposite end of the body 18 receive the side arms 11 of the yoke 10, the fingers 16 being received in any selected ones of the openings 19 in the side walls of the body, to permit an adjustment of the device to the wrist of the wearer.

10 The numerals 23 and 24 designate lids for the body 18, the lid 23 being longer than the lid 24, in order that the fingers 16 may be inserted readily into any of the seats 19. A pivot pin 25 joins the inner ends of the lids 23 and 24 together, and connects them to the side walls of the body 18. Each of the lids 23 and 24 has a depending skirt 26, and the skirts cooperate to surround the side walls of the body 18. In its ends, each of the lids 23 and 24 has notches 27, mating with the notches 21 in the ends of the body 18, to receive side arms 6 of the yoke 5, and to receive the side arms 11 of the yoke 10.

The yokes 5 and 10 are resilient, or at least bendable, but they retain the shape shown in 25 Fig. 2. It is possible to spring the arms 6 or the arms 11 either inwardly or outwardly, to cause the sockets 8 and 12 to be received between the parts 2 of watches of different dimensions. Before the device is placed on the wrist of the wearer, the lid 24 may be opened, to enable the operator to seat the arms 6 in the notches 21 and to engage the end member 7 with the anchor 20. Before the device is placed on the wrist of the wearer, the lid 23 may be opened, to enable

30 the operator to seat the arms 11 in the notches 21 and to dispose the fingers 16 in the appropriate seats 19, thereby adapting the device to previously-obtained measurements of the wearer's wrist. It will be noted that the connector 17 forms a receptacle in which, if desired, small 35 objects may be carried, not only in the interest of portability, but in the interest of secrecy, as well.

The cross piece 7 is spaced from one end of 40 the body 18, and since the fingers 16 are received in a pair of the seats 19, the fingers are spaced from the opposite end of the body. The result is that neither end of the connector 17 will be pulled out of shape.

45 Having thus described the invention, what is claimed is:

1. In a wrist band, a portable object, curved yokes assembled with said object, each yoke including side arms, the side arms of one yoke being connected terminally by a cross piece, the

side arms of the other yoke terminating in out-standing fingers, a connector comprising a box-like, open-topped body having notches in its ends for the reception of the side arms of the respective yokes, the cross piece being located within the body, the side walls of the body having longitudinally spaced seats, receiving the fingers adjustably, to vary the length of the band, and lids having their ends hingedly connected to the body, the lids having depending skirts, which combine to enclose the body, the end portions of the skirts having notches registering with

those of the body, one lid exposing the fingers and the other lid exposing the cross piece, when the respective lids are opened.

5 2. A wrist band constructed after the manner of claim 1, and wherein the cross piece is spaced from the adjacent end of the body, and an up-standing anchor on the body and engaged with the cross piece, to transfer pull to the bottom of the body and prevent pull from being transmitted to said adjacent end of the body.

10 GEORGE B. HOVEY.
